UNITED STATES PATENT OFFICE.

CHARLES THOMAS MASON, OF SUMTER, SOUTH CAROLINA.

ROCKING DISTRIBUTER FOR IGNITION SYSTEMS.

1,241,412.

Specification of Letters Patent. Patented Sept. 25, 1917.

Application filed November 16, 1916. Serial No. 131,729.

To all whom it may concern:

Be it known that I, CHARLES THOMAS MASON, a citizen of the United States, residing at Sumter, in the county of Sumter and 5 State of South Carolina, have invented certain new and useful Improvements in Rocking Distributers for Ignition Systems, of which the following is a specification, reference being had to the accompanying draw- 10 ing.

This invention relates to new and useful improvements in ignition systems, and more particularly to an ignition system for supplying a plurality of cylinders of an internal 15 combustion engine in which a distributor is used for distributing an ignition current first to one cylinder and then to another in proper time for igniting the explosive charge.

An object of the invention is to provide a 20 distributor which may be mounted independently of the magneto shaft and operated therefrom, and which distributor is so constructed that it may be shifted with the circuit breaker or interrupter for advancing 25 or retarding the spark for timing purposes.

A further object of the invention is to provide a distributor of the above character which rotates at a different speed than the 30 interrupter or breaker with means for shifting the distributor through the same angle of advance or retard as the circuit breaker or interrupter when the same is shifted for timing purposes.

These and other objects will in part be 35 obvious and will in part be hereinafter more fully disclosed.

In the drawings, which show by way of illustration one embodiment of the invention:

1 40 Figure 1 is a view, partly in side elevation and partly in section, showing a magneto having my improvements applied thereto;

Fig. 2 is an end view of the same with the cover plate for the circuit breaker removed 45 and a portion of the distributor broken away, showing the connection between the circuit breaker casing and the distributor casing whereby shifting of one shifts the other;

50 Fig. 3 is a view, showing more or less diagrammatically the arrangement of the terminals of the distributor and the devices for distributing the ignition current to these several terminals.

55 The invention is directed to a magneto having a rotor or inductor for producing a

plurality of E. M. F. and current waves for each rotation of the rotor or inductor. Associated with this rotor or inductor is a circuit breaker or interrupter which is so timed 60 as to break the primary circuit of the generating coil when the E. M. F. and current waves are at a maximum. Also associated with the circuit breaker or interrupter is a distributor. This distributor is mounted 65 free of the rotor shaft but is preferably actuated therefrom. The distributor may be rotated at a slower speed than the circuit breaker or interrupter so as to supply a number of cylinders of an internal combustion 70 engine. The present invention is directed particularly to the mounting of the distributor and the connecting of the same to the interrupter or circuit breaker box in such a way that, when the circuit breaker is 75 shifted for retarding or advancing the spark, the distributor will also be shifted to the same angle of advance or retard. This shifting of the distributor with the circuit breaker or interrupter permits of the using 80 of relatively small contact plates in the distributor so that the contact plates may be spaced a considerable distance apart and thus avoid any possible chance of the high tension current arcing between the contact 85 plates and the terminal contacts.

Referring more in detail to the drawings:

My invention is embodied in a magneto consisting of a supporting base 1 having 90 permanent magnets 2. Extending through the magnets is a rotor or inductor shaft 3 on which is mounted two flux-carrying elements 4 and 5. Coöperating with the rotor or inductor is a field structure which includes a generating coil, indicated at 6. This generating coil is provided with primary and secondary windings. One terminal of the secondary winding is indicated at 7. One terminal of the primary winding is 100 indicated at 8. The flux-carrying elements 4 and 5 are so constructed and positioned relative to each other and to the field structure as to produce four E. M. F. and current waves for each rotation of the shaft. This 105 shaft 3 of the rotor or inductor is connected to the main shaft of an internal combustion engine. The magneto shown in the drawings is intended to furnish a twelve-cylinder internal combustion engine. It will be understood, however, that the magneto may be constructed so as to supply an internal com- 110

bustion engine having a different number of cylinders and, therefore, it is obvious that the construction of the magneto and the distributor shown in detail in the drawings is 5 purely for the purposes of illustration. In operating my magneto for a twelve-cylinder engine, the shaft 3 is driven so as to make one and one-half revolutions for every single revolution of the engine shaft which 10 results in six E. M. F. and current waves for each rotation of the engine shaft. The distributor, as will be pointed out hereinafter, is provided with twelve terminals, and this distributor is, therefore, driven at a speed 15 ratio of one to three of the magneto shaft or one to two of the engine shaft.

The interrupter or circuit breaker is shown in the drawings for the purpose of illustration as consisting of two pairs of 20 contacts which are so constructed and operated that first one and then the other becomes effective for breaking the primary circuit. In other words, one of these contacts is opened while the other is closed and 25 opened, and while this remains open, then the first one is closed and opened. One pair of contacts is indicated in Fig. 2 of the drawings at 9. The fixed contact is carried by an anvil 10 and is connected to the primary 30 of the primary circuit. The other pair of contacts is also connected to this primary terminal 8. The movable contact of the pair 9 is carried by a lever 11 which is pivoted at 12 and carries a bumper 13 which cooperates with the rotor cam 14 35 which is fixed to the end of the shaft 3. The movable contact of the other pair of contacts, which is directly in rear of the contacts 9, is carried by a similar lever, and this 40 lever is operated by a cam 15 located alongside of the cams 14. These cams will not be described in detail as they form no part of the present invention *per se*, but are shown, described and claimed in my copending application Serial No. 37,130, filed June 45 30, 1915.

The levers for operating the movable contacts and the fixed contacts are all carried by a shiftable breaker box or casing 16. 50 This breaker box or casing may be shifted by a connection with an arm 17 or an arm 18, these arms being integral or otherwise suitably secured to the breaker box. Said breaker box is mounted so as to be shifted 55 about a bearing sleeve on the main frame of the magneto in a manner which is well-known in this art. Directly above the interrupter or breaker is the distributor.

This distributor consists of a central fixed 60 member 18 formed of suitable insulating material. Said member is mounted in a sleeve 19 carried by the magneto frame. Extending centrally into the member 18 is a conductor 20 which is connected with the 65 terminals 7 of the secondary winding. Said

central member is provided with six brushes, indicated at 21, 22, 23, 24, 25, and 26, respectively. Each of these brushes is electrically connected with the conductor 20. A spring 27 for each brush normally forces 70 the same outwardly in a radial direction away from the center of the member 18. The distributor also consists of a second fixed member, indicated at 28. This member is made of insulating material and carries 75 the twelve terminals, which are connected to the respective spark plugs of the twelve cylinders, which are to be furnished with the ignition current. These twelve terminals are located in two circular rows, the 80 front terminals being indicated at 29, 30, 31, 32, 33 and 34, respectively, while the rear row of terminals are directly in rear of the front terminals, and two of these terminals are indicated in dotted lines at 35 85 and 36, respectively. Each of these terminals include a yieldingly mounted brush which is forced inwardly radially of the distributor. The terminals are disposed in radial planes intersecting the brushes carried by the central member 18. Located between the inner and outer fixed members 18 and 28 is a rotating member 37 which is formed of insulating material. This rotating member is mounted on a sleeve 38 which 90 is carried by a suitable ball bearing 39. A gear wheel 40 is attached to said sleeve 38, and this gear meshes with a gear 41 on the rotor shaft 3. The gears 40 and 41 are preferably so proportioned that the gear 40 95 makes one revolution for every three revolutions of the gear 41.

The rotating member 37 of the distributor is provided with two pairs of contacts which are indicated at 42 and 43, respectively. 100 These pairs of contacts are similar in construction though oppositely arranged, that is to say, the contact 42 consists of an outer plate 44 and an inner plate 45 which are electrically connected, and these plates extend so as to be engaged by the brushes 21, 22, 23 and so forth, and so as to also engage the front row of terminals. The contact 105 members 43 also consist of outer and inner plates 44 and 45 electrically connected, and these are disposed so as to make contact with the brushes 21, 22, 23 and so forth, and the inner row of terminals carried by the member 28. The contacts 42 and 43 are so disposed that when one set is making contact between the brush 22 and the terminal 30, for example, then the other pair of contacts 43 is midway between the terminals 32 and 33 and also the brushes 24 and 25. As the member 37 rotates, if turned in the 110 direction of the arrow in Fig. 3, the pair of contacts 43 will soon join or electrically connect the plate 45 with the terminal in the inner row directly in rear of the terminal 43. Meanwhile, the pair of contacts 42 115

has moved to a position midway between the terminals 30 and 31, and also the brushes 22 and 23. As above noted, the distributor *per se* forms no part of the present invention, but has been described in detail in order that the invention may be understood.

The breaker box or casing 16 is provided with a pin 46, and this pin is adapted to engage a slot 47 formed in the member 28 of

10 the distributor. The central member 18 of the distributor is connected to the outer member 28 by means of suitable pins 48 which extend into recesses formed in the outer member 28 and also recesses formed 15 in the inner member 18. These members 18 and 28 are described above as fixed. They are fixed in the sense that they do not rotate during the normal operation of the distributor and yet they are shiftable. The mem- 20 bers 18 and 28 are secured to the frame by an annular ring 49 which is connected to the frame by bolts 49^a. This ring permits the members 18 and 28 to be freely shifted about the center of the distributor. The 25 breaker box or casing is shiftable for timing purposes, as above noted, and whenever this breaker box is shifted, the pin 46 will turn the fixed members 18 and 28 of the distributor about the center of the distributor.

30 but in the direction opposite to that in which the breaker box or casing is shifted. When, therefore, it is desired to advance the spark the breaker box or casing is shifted in the proper direction and through the desired 35 angle for advance, and this shifting of the breaker box will also shift the fixed member of the distributor through a similar angle of advance and, therefore, when the contacts are separated for producing an ignition cur-

40 rent in the secondary winding, the contacts either 42 or 43, which is effective at this time, will be properly positioned relative to the brushes on the inner fixed member 18 and the terminal brushes on the outer fixed 45 member 28. In other words, in all other distributors so far as I am aware, the contacts have to be of sufficient length to allow

50 for advance and retard of the spark but by my improvement where the distributor is shifted when the breaker is moved for advance and retard short segments may be used, that is, the length of the plates 44 and 45 may be relatively short and still make proper contact between the brushes on the 55 inner member 18 and the terminal brushes on the outer member 28 when the primary circuit is interrupted or broken. This relatively short length in the segments 44 and 45 gives greater distance between the seg-

60 ments and the terminal brushes of an idle or ineffective terminal and hence lessens the tendency of the spark to jump to the wrong terminal brush. For example, in a twelve-cylinder engine, although the terminals are 65 arranged in two rows, the angular distance

between adjacent terminals is sixty degrees. When the distributor has the fixed parts which are not shifted upon advance and retard of the spark, the angle of advance or retard must be somewhat limited otherwise 70 there is a danger of the spark jumping to the wrong terminal. By my improvement where the fixed terminals are shifted when the spark is advanced or retarded and through a corresponding angle of advance 75 or retard then this danger of the spark jumping to the wrong terminal is entirely avoided. In Fig. 2 of the drawings I have shown the breaker box and distributor as in an intermediate position in full lines, indicated at *b*, while I have indicated in dotted lines at *a* what may be considered the advance position, and then in dotted lines at *c* what would be the retarded position.

It is obvious that other forms of construction may be used in connection with the distributor and other forms of construction may be used in connection with the interrupter or circuit breaker. The essential feature consists in the shifting of the distributor through a corresponding angle of advance or retard when the circuit breaker or interrupter is shifted for timing purposes.

Having thus described the invention, what 95 is claimed as new is:—

1. An ignition system including in combination, a source of current, a circuit breaker, a distributor having a casing and a movable member therein mounted independently of 100 the circuit breaker, and means for simultaneously shifting the circuit breaker and said casing relative to said movable member for timing purposes.

2. An ignition system including in combination, a source of current, a circuit breaker, a distributor mounted independently of the circuit breaker, means for shifting the circuit breaker for timing purposes, and for simultaneously shifting the distributor in 110 an opposite direction through a corresponding angle.

3. An ignition system including in combination, a rotor shaft, a cam carried thereby, a circuit breaker operated by said cam, 115 means for shifting said circuit breaker about the cam for timing purposes, a distributor operated at a different speed from said cam, and means for shifting said distributor simultaneously with the circuit breaker.

4. An ignition system including in combination, a rotor shaft, a cam carried by said shaft, contacts actuated by said cam, a distributor mounted on a separate shaft from the rotor shaft and actuated thereby, and means for simultaneously shifting the contacts and the distributor for timing purposes.

5. The combination of a rotor shaft, a cam carried by said shaft, contacts actuated by 130

said cam, a shiftable casing carrying said contacts, a distributor including a rotating member and relatively fixed members, means for actuating said rotating member from the rotor shaft and at different speed from the rotor shaft, and means for simultaneously shifting the casing carrying the contacts and the fixed members of the distributor for timing purposes.

6. The combination of a rotor shaft, a cam carried by said rotor shaft, contacts actuated by said cam, a casing supporting said contacts, means for shifting said casing and contacts about the cam for timing purposes, 15 a distributor including a rotating member

and relatively fixed members, means for actuating said rotating member from the rotor shaft and at a different speed from the rotor shaft, said fixed members of the distributor being mounted so as to be shiftable about 20 the axis of said rotatable member of the distributor, and means for gearing the shiftable fixed member of the distributor to the casing carrying the movable contacts whereby the shifting of the casing also shifts the 25 fixed parts of the distributor through a corresponding angle for timing purposes.

In testimony whereof I hereunto affix my signature.

CHARLES THOMAS MASON.
